GARMENT HANGER

Howell Sherman, Fair Lawn, N. J.

Application October 3, 1955, Serial No. 538,216

3 Claims. (Cl. 223—95)

This invention relates to improvements in garment hangers and, in one of its more specific aspects, to an improved device for hanging trousers. The invention also pertains to a novel combination of an improved hanger for supporting a garment, such as a coat, and improved trouser hanging devices cooperatively and detachably associated therewith.

The primary object of the invention is to provide a trouser hanging device having improved features of design and construction.

Another object of the invention is to provide a trouser hanging device which, when used with a like or similar device, is adapted to engage the cuff portions of a pair of cuffed and conventionally creased trousers and suspend the trousers in inverted position in a manner to preserve the trouser creases and permit the weight of the trouser parts to work out wrinkles resulting from wear.

Another object of the invention is to provide a trouser hanger that may be readily and detachably secured to a convenient support such as a door, a wall or a coat hanger of the type that will be described further along herein. The parts of the trouser hanger are so constructed and arranged with respect to each other and with respect to the support and the trousers, when in active use, that the cuff portions of the trousers are maintained under tension along certain crease lines. As a consequence, the trousers hang freely and properly, thereby preserving its creases.

The invention has for a further object the provision of a device of the character indicated that is simple and compact in design, that is sturdy and durable in construction, that is adapted to be manufactured at low cost on a mass production basis, and that is capable of performing its intended functions in an entirely satisfactory manner.

With the enumerated objects and other objects in view, the invention comprises the devices, combinations and arrangements of parts set forth in the following detailed description and illustrated in the annexed drawings of preferred embodiments of the invention, from which the advantages of the invention will be readily understood by persons skilled in the art.

In the drawings:

Fig. 1 is a view in front elevation of a combination coat hanger and trouser hanging devices constructed in accordance with the invention and engaging a pair of cuffed trousers having conventional creases;

Fig. 2 is an enlarged isometric view of one of the trouser hanging devices shown in Fig. 1;

Fig. 3 is a view in enlargement taken along staggered line 3—3 of Fig. 1;

Fig. 4 corresponds to Fig. 2 and illustrates a modified form of trouser hanging device;

Fig. 5 corresponds to Fig. 3 and illustrates the manner in which the device of Fig. 4 engages portions of a pair of trousers during use;

2

Fig. 6 is an isometric view of another modification of the trouser hanging device of this invention;

Fig. 7 is a top plan view of Fig. 6; and

Fig. 8 is a perspective view of the device shown in Figs. 6 and 7 operatively associated with cuff portions of a pair of trousers.

Referring now to the drawings in which like reference numerals denote corresponding parts throughout the several views, a coat hanger is generally indicated by numeral 10 in Fig. 1. The coat hanger consists of a central hook 11, a pair of divergent parts 12 for receiving the shoulder portions of a coat or similar article of wearing apparel and a pair of arms 13 depending from the ends of the shoulder parts. Hook 11 is preferably made of metal while shoulder parts 12 and arms 13 may be made of any suitable material, such as wood, metal or plastic. Each arm is provided with a plurality of vertically spaced drill holes 14. A plurality of vertically spaced notches 15 may be formed in the outer edge portions of the arms. Drill holes 14 and notches 15 serve the same function and the hanger may be provided with either or both thereof, as desired.

Detachably secured to coat hanger 10 is a pair of identical trouser hanging devices 16 which engage legs 17 and cuffs 18 of a pair of trousers 19 as shown in Figs. 1 and 3, whereby to freely suspend the trousers in the manner illustrated in Fig. 1. The trousers are pressed to obtain conventional crease lines. The crease lines of the trouser legs are identified by numeral 20, the vertical crease lines of the cuffs by numeral 21 and the crease lines at the juncture of each trouser leg and cuff by numeral 22.

Device 16 is best shown in Fig. 2 and is made up of two units, namely a first unit 23 and a second unit 24 which is pivotally or hingedly connected to the first unit. Unit 23 may be made of any suitable material such as metal or plastic. This unit comprises a pair of spaced parallel plate members 25 each of which includes a generally vertical edge part 26 and a generally horizontal edge part 27. Integral with both plate members 25 is an upstanding resilient arm 28 that is spaced from vertical edge parts 26 of the plate members, as indicated at 29. It will be observed that arm 28 projects above horizontal edge parts 27 of the plate members.

Unit 24 is in the nature of a connector and is preferably made from a length of relatively heavy gauge wire that is bent to obtain a rectilinear central part 30, an eye part 31 at one end and a hook part 32 at its other end. Eye part 31 extends through an opening 33 in the upper end of arm 28 and forms a pivot or hinge connection therewith. Hook part 32 is adapted to register with a selected drill hole 14, as shown in Fig. 1, or with a selected notch 15. It will be apparent from the drawing that hook part 32 may be easily and quickly attached to or detached from an arm of the coat hanger.

If desired, devices 16 may be readily secured to various types of supports instead of to the coat hanger. Such supports include doors, walls or other convenient locations in the home. For example, if hangers 16 are to be mounted on a door, hook parts 32 of the devices may be placed in engagement with corresponding screw eyes, screw hooks, nails or the like that are fastened in proper location to the door.

Devices 16 are adapted to be readily placed in engagement with the cuff portions of the trouser legs and suspend the trousers from the coat hanger as shown in Fig. 1. At the time each device 16 is connected to the trouser legs, its plate members 25 are inserted between corresponding legs 17 and cuffs 18 and arranged so that the parts assume the relative position shown in Figs. 1 and 3 with each device connected to a corresponding arm 13 of the coat hanger. It will be observed that the vertical

edge part 26 of each plate member is positioned against and along the inside of a cuff crease and the horizontal edge part 27 is positioned against and along the inside of the crease of that cuff and trouser leg. The distance between coat hanger arms 13 is greater than the end width of the trouser legs. Consequently and due to the weight of the trousers, central parts 30 of units 24 are inclined. Also, due to the weight of the trousers and the relative position of the parts, the cuff portions of the trousers are stressed in tension and the trousers are freely suspended in a manner to preserve its creases and allow wrinkles, occasioned by wear, to be smoothed out.

Figs. 4 and 5 illustrate a modified form of trouser hanging device that is generally indicated by numeral 35 and that is similar in many respects to device 16. The device 35 consists of a first unit 36 and a second unit 37. Unit 36 includes four spaced parallel plate members 38 of equal size and like configuration, each plate member having a generally vertical edge part 39 and a generally horizontal edge part 40. An arm 41 is integral with each plate member and is spaced therefrom as indicated at 42 (Fig. 4). This arm extends above the horizontal edge parts 40 of the plate members. The upper end of arm 41 is bifurcated, as indicated at 43, and carries a pin 44.

Unit 37 consists of a strap type connector 45 that is preferably made of a strip of metal or plastic material. One end of connector 45 registers with bifurcation 43 and forms a pivot connection with pin 44. Secured to the other end of connector 45 is a pivoted hook member 46 that is adapted to be inserted in a selected drill hole opening 14 or notch 15 of a coat hanger arm 13.

A pair of devices 35 is adapted to be connected to coat hanger 10 and trousers 19 so as to suspend the trousers in the manner shown in Fig. 1. It will be noted from an examination of Fig. 5, that each leg and cuff of the trousers is engageable by two plate members 38 instead of by only one such plate member as in the case of device 16 earlier described.

Reference is next had to Figs. 6, 7 and 8 which illustrate another modified form of trouser hanging device which is generally identified by numeral 47. As in the case of devices 16 and 35, device 47 consists of a pair of units, namely, a first unit 48 and a second unit 24 (earlier described).

Unit 48 is made from a single length of resilient wire that is bent, as shown, to obtain a pair of spaced parallel members 49. Each member 49 comprises a generally vertical part 50 and a generally horizontal part 51. An upstanding hair pin shaped arm 52 is integral with and spaced from members 49 as indicated at 53. The upper

end of arm 52 defines an open loop that is engaged by eye part 31 of unit 24.

A pair of devices 47 is adapted to engage the cuff portions of trousers 19 and suspend the trousers in substantially the same manner outlined above in respect to device 16.

From the foregoing, it is thought that the construction, operation, and advantages of the herein described invention will be apparent to those skilled in the art, without further description; and it will be understood that various changes in the size, shape, proportion and minor details of construction may be resorted to without departing from the spirit, or sacrificing any of the advantages of the invention.

I claim:

1. In a device for hanging trousers, a first unit and a second unit, said first unit being of one-piece construction and comprising a plurality of spaced plate members, each plate member having a generally vertical edge and a generally horizontal edge extending in one direction from the upper end of the vertical edge, each plate member being adapted to be inserted between portions of a corresponding leg and cuff of a pair of conventionally creased inverted trousers in a manner that its vertical edge is positioned substantially against and along the inside of the cuff crease and its horizontal edge is positioned substantially against and along the inside of the crease of such cuff and trouser leg, each plate member including a substantially coplanar extension at its lower end and extending in a horizontal direction away from the body of the plate member, and an upstanding plate-like arm secured to each extension and spaced from and generally parallel to the vertical edge of each plate member, said second unit comprising a part pivotally connected to the arm of the first unit and a part that is adapted to be secured to a support.

2. A device according to claim 1 wherein said plurality of spaced plate members consists of two such members.

3. A device according to claim 1 wherein said plurality of spaced plate members consists of four such members.
